FIG. 1

FIG. 2

FIG. 3

To all whom it may concern:

Be it known that I, Robert Davol Budlong, a citizen of the United States, residing at Skokie, in the county of Cook, State of Illinois, have invented a new, original, and ornamental Design for a Television Cabinet, of which the following is a specification, reference being made to the accompanying drawing forming a part hereof.

Figure 1 is a perspective view of a television cabinet showing my new design;

Figure 2 is a fragmentary front elevational view showing the control knob in detail; and

Figure 3 is a fragmentary side elevational view of the control knob detail shown in Figure 2.

The essential features of my design reside in the portions shown in full lines.

The side of the cabinet not shown is similar to the side shown in Figure 1, and the rear of the cabinet is unornamented.

I claim:

The ornamental design for a television cabinet, substantially as shown and described.
